UNITED STATES PATENT OFFICE.

JAMES LILLY CLARK, OF LOS ANGELES, CALIFORNIA, ASSIGNOR OF ONE-FOURTH TO
R. C. INGRAM, OF LOS ANGELES, CALIFORNIA.

DESIGN FOR A BADGE.

51,919.

Specification for Design.

Patented Apr. 2, 1918.

Application filed February 11, 1918. Serial No. 216,636. Term of patent 7 years.

To all whom it may concern:

Be it known that I, JAMES LILLY CLARK, a citizen of the United States, residing at Los Angeles, in the county of Los Angeles and State of California, have invented a new, original, and ornamental Design for Badges, of which the following is a specification, reference being had to the accompanying drawing, forming part thereof.

The figure is a face view of a badge, showing my new design.

I claim:

The ornamental design for a badge, as shown.

JAMES LILLY CLARK.
